UNITED STATES PATENT OFFICE.

WESTON M. FULTON, OF KNOXVILLE, TENNESSEE, ASSIGNOR TO THE FULTON COMPANY, OF KNOXVILLE, TENNESSEE, A CORPORATION OF MAINE.

VALVE.

1,370,532.

Specification of Letters Patent. Patented Mar. 8, 1921.

Original application filed April 20, 1914, Serial No. 833,237. Patent No. 1,176,535, dated March 21, 1916.
Divided and this application filed March 3, 1916, Serial No. 81,912. Renewed January 19, 1921.
Serial No. 438,530.

To all whom it may concern:

Be it known that I, WESTON M. FULTON, a citizen of the United States of America, and a resident of Knoxville, Tennessee, have 5 invented a new and useful Improvement in Valves, which invention is fully set forth in the following specification.

This invention relates to self-acting valves, and more particularly to valves of this class 10 in which the operation of the valve is controlled by a pilot valve, operated by hand or by automatic control means.

In valves of this type, there is provided a casing separated into a high pressure receiving side and a low pressure delivery side 15 communicating with each other through an opening controlled by a valve usually operated by a piston the movement of which is controlled by a pilot valve operated by 20 more or less delicate outside means, such as centrifugal governors, timing apparatus, thermostatically controlled elements, low pressure systems, magnetic devices operating from a distance, etc. Owing to the 25 difficulties experienced in making the piston fluid-tight, leakage often occurs around the piston, thereby resulting oftentimes in the unexpected operation of the valve. While attempts have been made to compensate for 30 this leakage by use of a large pilot valve, it is found that the leakage defect is usually progressive while the provision for caring for it remains constant, with the result that the leakage difficulties continue; furthermore, the larger the pilot valve the more 35 work is thrown on the device which operates this valve, thereby reducing the sensitivity of the device.

With the object of overcoming the above 40 objections, my invention resides in providing in a self-operated pilot-controlled valve, such as used for reducing from high to low pressure, a collapsible and expandable corrugated vessel having an operating connection with the valve member on the low pressure side of the valve and being in communication with the high pressure side through a conduit controlled by a pilot valve. The valve is moved into opening position against 45 tension, such as afforded by a spring, when high pressure fluid is permitted, by the pilot valve, to accumulate in the vessel and is moved into closing position, when the vessel

is vented into the atmosphere or into the space on the low pressure side of the valve. 55

The use of my collapsible and expandible vessel in the manner described avoids leakage past a piston and reduces this loss to merely that required for lowering the pressure in the vessel to that of the atmosphere, 60 or that in the low pressure system. The construction permits a very small pilot valve to be used, thereby reducing the power to operate it and consequently increasing the sensitivity of control. 65

The present application is a division of my application Serial No. 833,237, filed April 20, 1914, which has matured into U. S. Patent No. 1,176,535 of March 21, 1916, wherein the present invention is described 70 but not specifically claimed.

The collapsible and expandible metal vessel which I prefer to employ consists of a flexible corrugated sheet metal wall of the character shown and described in my U. S. 75 Patents Nos. 887,084, 903,465, 947,229, 967,010, 975,519, 976,060 and 979,460, having one end stationary and secured to the wall of the valve casing, the opposite movable end being closed by an inflexible end wall 80 which is connected with the valve to be operated.

Referring to the drawing, which presents a vertical longitudinal section of a valve embodying my invention, 34 is a valve casing preferably having a flanged inlet 35 and a flanged outlet 36 for connecting with a pipe line. A partition 37 separates the valve casing into high and low pressure compartments, respectively, and has an 90 opening in which is secured a valve seat 38. The casing is provided with an enlargement 39 on the low pressure side of the partition 37 for receiving a collapsible and expandible vessel 40, preferably of the kind 95 described in my patents above referred to. The upper end of the vessel is provided with a flange 41 for supporting it on the flanged edge of the casing wall 39 and is held in place under a washer 42 by a closure 43 adapted to be bolted or otherwise secured to the casing. The lower end of vessel 40 is closed by an inflexible wall 44 to which is secured a valve stem 45 carrying a valve 46 adapted to engage the seat 38 and which is 100 pressed toward seating position by a spring 105

47 resting at its lower end in a cup 48 formed on the inner side of a cap 49 which has a socket 50 for guiding the lower reduced end of the valve stem 45. The casing 5 closure 43 is provided with a chamber 51, the upper end of which is adapted to be closed by the threaded extension 52 of a pilot-valve casing 53. In the body of closure 43 is drilled a passage 54 closed at its 10 outer end by a plug 55 and opening into chamber 51 at the opposite end. This passage has a side opening 56 adapted to register with a passage 57 in the wall of the main casing 34, thus providing open communication between the high pressure part 15 of the line and chamber 51. In the pilot-valve casing 53 is provided a chamber 58 which is adapted to communicate with chamber 51 through a valve-controlled port 20 59 formed in a screw-plug 60. This passage is controlled by a pilot-valve 61 which is carried at the end of a hollow stem 62 passing through a packing joint 63 of usual construction. The valve stem 62 has a side 25 duct 64 which permits communication between chamber 58 and a place of lower pressure, such as the atmosphere, when the stem is lowered by means such as a thermostat or other suitable operating device. Communication 30 is established between chamber 58 and the interior of the collapsible and expandable vessel 40 through a passage 65 in the wall of casing 53 and a registering passage 66. A tight joint is provided between parts 53 and 35 43 by packing 67. 71 is a portion of a frame which may be secured to the casing for supporting any suitable means for actuating the pilot-valve stem 62.

From the above description, the operation 40 of the device will be readily understood without detailed explanation. With the parts in the position shown, the interior of the collapsible and expandable vessel communicates with the high pressure system, 45 through a pilot-valve controlled port 59, and under this pressure the vessel extends against

the action of spring 47 and against the low pressure on the exterior of the vessel. Valve 46 under these conditions is held in open position. When valve stem 62 is lowered by 50 operation of a thermostat or other operating device, passage 59 is closed and the collapsible and expandable vessel 40 is vented to the atmosphere or other place of lower pressure through duct 64 and the passage in 55 the valve stem. Spring 47 and the low pressure of the line now are permitted to become effective to lift the valve 46 to seating position where it is held by the spring and the high pressure in the line until again 60 opened by operation of the pilot-valve.

From the above, it will be seen that the use of a sliding piston in the type of valve described is obviated, together with its leakage difficulties, and that the small size of 65 opening in the pilot-valve makes it possible to use very delicate operating means for controlling this valve.

What is claimed is:—

In a valve of the character described, a 70 conduit, a partition therein separating the conduit into high and low pressure sections and provided with a port, a valve controlling said port, a collapsible and expandable corrugated vessel having a movable end 75 wall subjected to the pressure in said low pressure section and connected to said valve, a passage between said high pressure section and the interior of said vessel, a rectilinearly-movable pilot-valve controlling 80 said passage, and a passage in the stem of said pilot-valve adapted to be brought into communication with the interior of said vessel when said pilot-valve is moved longitudinally to close said first passage. 85

In testimony whereof I have signed this specification in the presence of two subscribing witnesses.

WESTON M. FULTON.
